TELEPHONE AMPLIFICATION

Heinrich Karl, Jersey City, N. J.

Application December 18, 1936, Serial No. 116,462

11 Claims. (Cl. 179—2)

This invention relates to an amplifier that can be readily connected to and disconnected from any telephone at will. According to one modification of the invention this may be accomplished by coupling the receiver or ear phone of any make of telephone to the amplifier or radio set, so that the person that has a conversation through the telephone does not need to hold the ear phone to the ear and instead can use the one hand for writing down notes and the other hand for holding the pad or paper or other things. It is also to advantage to persons that have a temporary or chronic impairment of hearing and it is to advantage to the public in general when it deals with callers that are hard to understand on account of a feeble voice or of a too shrill voice or on account of some peculiarities of the voice whose imperfection is still aggravated by the telephone, whereby in such cases anybody can easily step up or down a voice to such a degree that would suit the ear of the hearer for better understanding the conversation.

It is especially a need for public telephones where thousands of people of different capacities of hearing must use the same telephone. In this instance it must be mentioned also that fastidious people hate to touch or to hold to the ear a telephone receiver or ear phone which thousands of different people had used before. From a sanitary as well as from a practical view point the invention responds to a public demand.

I am aware that amplifiers for telephones have been used already but these are of a different construction and the connections are of a different character and they are not constructed for the use in pay stations whereby anyone can take advantage of them by inserting a certain coin.

One of the objects of this invention is therefore the creation of an amplifier or radio set that is easily and quickly attachable to the receiver or ear phone of any telephone and therefore capable of amplifying the voice that is transmitted through the telephone connections.

Many men and women like to walk around while there is a conversation because in this way they can think better. It may be a temperamental habit. Many people like it also to have their hands free for making notes while talking and listening to the telephone.

The amplifier is not only usable for telephone conversation but it can be used also in connection with an antennae as a radio receiver and amplifier by simply making a connection with the antennae until there is a telephone call which will be announced by a bell or a buzzer.

A further object of the invention is the creation of diaphragms of mostly non-metallic consistency which are to transmit the voice of the speaker with greater clarity, resonance and volume than it is possible with diaphragms made from metal alone which all create a shrill metallic sound that hurts the normal ear.

A still further object of the invention is to amplify the voice to such volume or strength that the hearer does not need to put the ear phone or receiver to his ears. A still further object of the invention is to enable a person using a telephone pay station to amplify the voice of another person with which it has a telephone conversation by simply inserting a certain coin in the amplifying outfit and that said coin causes various circuit connections which again connect the various circuits necessary for amplifying the voice over the telephone.

A still further object of the invention is to enable a person using a telephone pay station to amplify the voice of another person with which it is connected over the telephone and to selectively make such connections with push buttons or with a knob as will best suit the hearing without the need of employing the ear piece or receiver which, however, may be used by such persons that may not need the or want to pay for amplification.

Still another object of the invention is the particular arrangement of the delicate parts of the amplifying apparatus that protects them from destruction by mischievous persons.

Still another object of the invention is the use of the weight of a person to prepare the amplifying apparatus in a pay-station or booth for the use thereof and to automatically restore all the mechanisms to a non functional state when that person leaves the floor of the station or booth.

Still another object of the invention is to automatically record the amount of coins inserted in the amplifying apparatus at a pay station.

Still another object of the invention is the creation of a receiver with such diaphragm that creates a clearer and more sonorous sound than it is possible with all-metal diaphragms.

Still another object of the invention is the creation of a combination of a diaphragm of lacquered paper or cloth with an all-metal diaphragm whereby the paper or cloth diaphragm will create the correct sound waves while the all-metal diaphragm will transmit them for the transformation into electro-motive forces.

Still another object of the invention is the creation of means for momentarily shutting off

the voice coming over the amplifier and such means for damping a voice that is amplified in excess of the desired strength.

Still another object of the invention is the creation of a support with soft padding material that is adapted to exclude external sounds from the receiver or ear phone when coupled to the transmitter of the amplifier and said support having the impression of the shape of the receivers or ear phones front, and clasping means adapted to hold the receiver or ear phone close against the padding material near the diaphragm of the transmitter for the amplifier or radio set.

Still another object of the invention is the creation of novel arrangements in connection with the metallic diaphragm for obtaining the most desirable transformation of the sound into the electro-motive force for amplification.

Other advantages and features will appear in the detailed specification.

In the accompanying drawings which show the invention best suited for illustration the

Figure 1 shows in elevation and partly in section the switch arrangement of the amplifying apparatus of a paying station in which the regular telephone transmitter and receiver is also installed and where for the simplification of service the customer may get amplification in three stages by the simple manipulation of pushing down one of a series of press buttons with one of which will be obtained an amplification to "Normal voice" and with another to "Loud" and with still another to "Very loud", respectively; means for interrupting at will the voice heard over the amplifier and means for damping that voice are also employed.

Figure 2 shows an elevation partly in section on the line 2-2 of Figure 1 showing chiefly the mechanism for the preliminary functioning that is operated automatically when the coin is dropped in and which includes the setting of certain switches showing also the automatic recording of the amount of coins that have been inserted.

Figure 3 shows an elevation partly in section on the line 3-3 of Figure 1 with parts broken away to show the switch arrangement from the side.

Figure 4 shows a circuit with the chief characteristics of a telephone line that is controlled at the central or connecting station; the transmitter and receiver on the left hand end of the telephone line being a pay station with telephone amplifier of the character exemplified in Figure 1 while at the right hand end of the telephone line is represented a transmitter and receiver that might be situated in a private home, or office etc. where the amplifier is also connected to an antennae for receiving wireless transmission in form of a regular radio set whereby the telephone can be switched in and the radio connections with the antennae switched out.

Figure 5 shows schematically a typical three radio tube amplifying electrical diagram in which the various switching units are introduced that are shown in Figures 1 and 3; the receiver of the regular telephone is also shown being coupled in such way to the transmitter of the amplifying set that outside sounds will be kept out.

Figure 6 shows in section and somewhat enlarged the transmitter of Figure 5 and the parts of soft rubber for keeping out outside sounds.

Figure 7 is an enlarged sectional view of parts for holding the diaphragms of the amplifier transmitter as shown in Figures 5 and 6.

Figure 8 shows the scheme of keeping a special

amplifier transmitter and receiver apart from the regular telephone receiver (and transmitter) in order to prevent damage to the delicate diaphragms of the amplifier-transmitter.

Figure 9 shows the details of the combined receiver and amplifier transmitter as used in the scheme of Figure 8, showing also a scheme for the transformation of the sound waves into electro-motive forces that is different from that shown with the transmitter of Figures 5, 6, and 7.

Figure 10 shows another scheme for protecting the delicate diaphragms of the amplifier transmitter from being damaged.

Figure 11 shows a receiver or ear phone with the improved diaphragm also used on the combined receiver transmitter of Figures 8 and 9 and of Figure 10.

Figure 12 shows in section and somewhat enlarged the diaphragm of the receiver of Figures 9, 10 and 11.

Figure 13 shows a front view of the diaphragm of Figure 12.

Figure 14 shows in side view and partly in section a commutator with a dial that is also employed on the amplifier of the right hand end 26 station of the telephone line shown in Figure 4 and which substitutes the push button switches of the amplifier of a pay station as shown in Figures 1, 2 and 3; the commutator is set at "Normal voice" strength.

Figure 15 shows the dial and knob of Figure 14 in front view.

Figures 16, 17, 18 and 19 show the positions which the movable contacts take on the commutator of Figure 14 while it is being turned the view is taken on the line 14-14 of Figure 14 looking to the left. In Figure 16 is shown the "off" position, in Figure 17 the position for the "Normal" voice strength, in Figure 18 the position for "Loud" and in Figure 19 the position for "Very loud";

Figure 20 shows schematically the way the commutator of the switching arrangement of Figures 14, 15, 16, 17, 18 and 19 can be automatically returned to the "off" position when the caller leaves the telephone booth.

Referring to Figures 1, 2 and 3 the numerals 1, 1a, 2 and 2a designate the upright walls of a telephone booth of a so-called pay station that might be made sound-proof against outside sounds as known. 3 represents the floor of the booth which is spaced from the floor 4 of the room in which the booth is situated. Floor 3 is pivoted as at 5 so that it will be moved on the pivots 6 when a person steps on it whereby the weight of that person presses the floor 3 down and keeps it in that position as long as it stands or otherwise keeps its weight on the floor. That person might even sit down on the seat 7 (seen in Figure 2) which can be moved up by turning it on a pivot 8 and secure it to the wall of the booth by suitable means, such as clamps, hooks, etc. so as to be out of the way when that person prefers to stand. A standard 9 is pivotally secured to the underside of the seat 7 that it will stand on the floor 3 when the seat 7 is brought into the horizontal position. The weight of that person sitting on that seat 7 is then also transmitted to the floor 3 and the latter is pressed down. Springs 10 are chiefly arranged for returning the floor 3 to its normal uppermost position or level when the person leaves the booth which indicates that it has finished the conversation. Secured to the end 11 of the floor 3 are two vertical rods 12 and 13 which hold

a horizontal bar 14 at its extreme ends. Bar 14 is so arranged that it will push a series of switch devices, to be described subsequently, to their normal positions when the floor 3 is in its uppermost level in which said bar 14 is also pushed to its uppermost position. When the floor 3 and consequently also bar 14 is pushed down through the weight of a person the series of switch devices are then prepared for being used but they 10 will not respond unless the various preliminary steps are undertaken usual with telephone. First, the receiver 15 is to be taken from the hook 16 after the correct amount of coins has been introduced into the slot 17 and the connection has 15 been made at the central station A shown in Figure 4 either by calling or by other means now in use.

While the operator at the central station A connects the caller with the phone demanded or 20 before that or after it has become necessary to amplify a voice that could not be understood on account of being too feeble or distorted the caller has to drop the coin, say a 5 cent piece, into the slot 18 shown in Figures 1 and 2 where- 25 by the obstacle will be removed that otherwise would prevent the amplification of that voice. Said obstacle consists partly of a pivoted lever 20 that is preferably of metal so as to have a certain weight. The pivot thereof that is indicated by 21 is secured to the booth wall 2a. At its front end that lever 20 has an extension 22 (see Figure 2) with bevelled upper surface and horizontal underside. For holding said lever 20 in the horizontal position a bolt 23 is so arranged 30 that it forms a support that bears with its upper horizontal surface against the horizontal underside of the extension 22. Bolt 23 is retractable against the tension of a spring 24 and that retraction is achieved through electro-magnetic 35 force. Though mechanical non-electro-magnetic means may be employed, the use of an electro-magnet is preferable because a greater pull can be exerted upon the bolt 23 than it would be possible with purely mechanical means on 40 structures of that character where a coin must cause the action.

In order to permit the electro-magnet 25 to 45 attract the bolt 23 there is an iron bar 26 secured crosswise to the bolt 23 and distanced from the poles of the electro-magnet 25 only as much that it will be attracted when the electro-magnet becomes energized. The winding 27 of that electro-magnet 25 forms part of a circuit that includes the battery 28, two contacts 29 and 50 30 of which the latter is of a more springy and movable character than the contact 29. Contact 29 is connected to the battery 28 by means of the wire 31. The winding 27 has one of its terminals connected to the wire 32 which leads to the other side of the battery 28 and its other terminal to wire 33 that leads to the contact 30. Contact 30 is preferably made of a thin steel sheet that is secured at some point in the slot 18 and which is distanced with its lower end 55 a little from the contact 29 so as to normally keep the circuit open. Contact 30 is therefore as much extended into the slot 18 that a coin of certain size such as a nickel will force the contact blade 30 against the contact 29 when it falls 60 down the slot. Not only the size of that coin but also the impact causes it to push the delicate springy contact 30 upon the contact 29. Through the attraction of the bolt 23 through the energized electro-magnet 25 the lever 20 loses its 65 support on its front end and drops to the in-

clined position shown by the dotted lines. The coin 31a thus rolls down on the then still more inclined upper surface channel provided for on that lever and drops into the box 32a through the slot 33a. The box 32a may be secured to the wall 2a. A lock 34 keeps the front wall 35 locked that is so formed as to serve as a cover for the opening that permits the removal of the coins dropped in the box. That cover or wall 35 is hinged to the box as at 36. The lever 20 10 will be restored to its normal horizontal position by the bar 37 which is secured with its one end to the rod 13 (see Figure 1) and with its other end to a rod 38 that is secured to the end 11 of the floor 3. When the person leaves the booth, 15 the floor 3, rods 13, 38 and the bar 37 lift then the lever 20 and while moving into its horizontal position the extension 22 thereof contacts with its foremost edge the bevelled side of the bolt 23 thus forcing the latter to recede against the 20 tension of the spring 24 until it (the extension 22) passes said bolt whereby the latter snaps forward again and forms the support for the lever 20. 25

The lever 20 performs a number of functions, one of which is the setting of the switch-bar 40 to current conducting position when the lever 20 is in the inclined position and the placing of that switch-bar 40 into current interrupting position when the lever 20 is in its horizontal position. For this purpose a bar 41 is secured to the lever 20 by one of its ends and passed through a hole at the lowermost part of the switch bar 40 and the other end of the bar 41 is suitably secured to a pivot 42. The electrical connections thus completed or interrupted will be described later. Another function which lever 20 performs in co-operation with the bar 41 is to allow the switch-bars 43 and 44 to be moved down when it (the lever 20) is in the inclined position and 40 to restore to or keep these switch bars in the position in which they interrupt the circuits to be described later when it (the lever 20) goes to and stays in the horizontal position. While switch bar 40 will be pulled down by the bar 45 41, the switch bars 43 and 44 will stay in their uppermost position. This is obtained by providing each of the switch-bars 43 and 44 with a longer lower end part that has a relatively long slot in which the bar 41 can move down without 50 pulling these switch bars down. Bar 41 will move any of these switch bars 43 and 44 up again should they be moved down through means that will be described subsequently.

Another function which the lever 20 performs 55 is that of moving a ratchet wheel 45 of a recording device one step farther every time it (the lever 20) goes to its inclined position. The spring sustained finger 46 that is pivoted to the lever 20 pushes the ratchet wheel 45 and when the lever 20 moves to its horizontal position the finger 46 60 is moved into engagement with one of the next following teeth of that ratchet wheel by the spring 47.

On the axle of the ratchet wheel 45 is secured 65 a spool 48 to which is fastened the end of a strip of paper 49 that again is wound on another spool 50 against which an indicating device 51 with ink container is moved every time the electro-magnet 25 attracts the bar 26 to which said 70 indicating device is attached. The latter may consist of a pen connected with the ink container in such way that there will be supply of ink every time the pen touches the paper roll 50. The collector of the dropped in coins may affix 75

the date of the collection of the money right behind the last mark made by the indicating device.

A still further function of the lever 20 is that of an electrical switch which when in connection with a circuit may cause the announcing at the central station or other place of the dropping of a coin in the slot of the amplifier.

In Figure 4 there is at 53 indicated in a diagrammatic way how the electrical connection in regard to the other circuit schemes may be made. In Figure 2 the stable contact is indicated by 54 and the movable contact by 55.

So far all those functions have been described that are performed by the apparatus when a person enters the booth and drops the required coin into the slot 18 which are the steps prior to the choosing of the degree of amplification of the voice heard over the telephone.

For better comprehending the electrical connections or disconnections which are performed by the switch bars that again are operated by the person using the buttons 56, 57 and 58, the diagram of the amplifying circuits of Figure 5 may serve. The button 56 that is shown in Figures 1 and 8 serves for adjusting the switch bar 60 in such way as to cause the amplifier to increase the voice over the telephone to the strength of a normal speaking voice of a person standing in front of the listener. It is thus apparent that the first unit of the amplifier that includes the vacuum tube 61 must be so adjusted that an amplification up to the strength of the normal speaking voice will be obtained at the first output, which will be obtained through suitable connections with the secondary winding 62 of the transformer 63 and which include the wire 70, the contact 68, the current conducting part 66, the contact 72 and the wire 71 as far as the one of the terminals of the secondary winding 62 is concerned and the other terminal of that winding is connected by the wire 218 to which is connected the wire 219 which again is connected to the loud speaker 64. It will be noted that also the secondary windings of the transformers 102 and 112 are in electrical connection with the wire 218 and through the wire 219 with the loud speaker 64. While the amplifier is not used the switch bar 60 is therefore placed in such position that it will interrupt the electrical connection with the loud speaker 64 when the button 56 is in its uppermost position. In this position the switch bar 60 being rigidly united with the button 56 is also in its moved up position. This switch arm comprises two current conducting parts 65, 66 and an insulated part 67. A contact 68 that is pressed against the switch bar 60 by means of a spring 69 (see Figure 1) and which is connected by the wire 70 to the second winding 62 of the transformer 63 contacts with the insulation 67. To the conducting part 66 may be affixed the wire 71 that leads to the loud speaker 64 but according to the drawings there is a special contact 72 so arranged opposite the contact 68 that it presses against the switch bar 60 through the urge of a spring 73 so that the contact 68 will have an adequate counterpressure at all times. Another pair of contacts 74, 75 is arranged similarly to the contacts 68, 72 but they contact with the conducting part 65 when the switch bar 60 is in its uppermost position. In this position an electrical connection is created between the second winding 62, the wire 70, respectively, and the grid 76 of the second vacuum tube 77, whereby the wire 78

electrically connects the contact 75 with the grid 76.

If all the connections are intact that create the electro-motive force set up in the transformer 63 which includes also the then pushed down switch bar 40 with its conducting parts 79, 80 that are then contacted by the contacts 81, 82 and 83, 84, respectively, whereby the circuits for the filament 85 and for the plate 86 will be closed thereby, that electro-motive force will be transformer into sound waves by the loud speaker or cone 64 when the button 56 and consequently the switch bar 60 is pushed down whereby the contacts 68, 72 come into electrical contact with the conducting part 66. The contacts 74 and 75, however will come into contact with the insulation 67 whereby the electrical connection between the second winding 62 of the transformer 63 will be cut out from the grid 76 of the vacuum tube 77.

Assuming, however, that the amplification through the connections so far described are not sufficient for the listener on the amplifier and that a still greater amplification is desired which would be denominated "Loud" according to normal standards of hearing, the second button 57 is to be pressed down which thereby will bring the spring urged contacts 88, 89 into contact with the conducting part 90 of the switch-bar 91. The spring urged contacts 92 and 93 would then come in contact with the insulation 94 and the switch bar 43 which thereby will be pushed also to its lowermost position through the switch bar 91 will bring the conducting parts 95 and 96 into contact with the spring urged contacts 97, 98 and 99, 100, respectively. The result is then the electrical connection between the second winding 101 of the transformer 102 with the loud speaker 64 by means of the wire 103, contact 88, conducting part 90 of the switch bar 91, contact 89, wire 104 and wire 105.

Furthermore, the interruption of the connection is also obtained between the wire 103 and the grid 106 which latter is electrically connected with the contact 93 by the wire 107 while the contact 92 is connected by the wire 108 to the wire 103; furthermore, the closing of the circuit for the filament 109 through the contacts 97, 98 and the conducting part 95 is also obtained as well as the closing of the circuit for the plate 110 through the contacts 99, 100 and the conducting part 96.

For a still greater amplification denominated "Very loud" another vacuum tube 11 is used together with the circuits necessary therewith including the transformer 112 whose second winding 113 is connected to the wire 114. The switch bar 115 to which is secured the push button 58 is similar to the switch bar 60 and the switch bar 91 and serves for the electrical connection of the wire 114 with the wire 105 by means of the spring urged contacts 116, 117 and the conducting part 118 when that switch bar is pushed down. Other contacts pressed against the switch bar 115 would have a useful purpose only when further amplification would be made through a fourth or more vacuum tube or tubes.

The switch bar 44 which will be pressed down by the switch bar 115 when the latter will be pushed down, closes the circuits of the filament 119 and of the plate 120 through the spring urged contacts 121, 122, the conducting part 123, the spring urged contacts 124, 125 and the conducting part 126, respectively.

In order to have an amplification either "Nor-

mal voice", "Loud" or "Very loud" it is necessary to have the two other upper switch bars pushed up that are used for the other stages of amplification so that the electro-motive force will be concentrated only to the one stage of the amplification desired. If, for instance, the switch bar 60 is pushed down, the switch bars 91 and 115 must be pushed up so that the loud speaker 64 will be influenced only by the electro-motive force set up in the coil 62.

If, however "Loud" is desired and consequently the switch bar 91 is pushed down, the switch-bar 60 and the switch bar 115 must be pushed up, first in order to avoid a louder voice than desired and furthermore to have the connections over the contacts 74, 75 and the conducting part 65 in alignment so that the grid 76 will receive the impulse from the electro-motive force set up in coil 62.

Should then "Very loud" be desired as the degree of amplification and consequently the switch bar 115 pushed down, the switch bars 60 and 91 must then be in their pushed up positions in order that the combined output of the two other amplification units reach the third amplification unit.

For automatically moving the two other switch bars up if they should not be in the pushed-up position while the third switch bar is being pushed down which third switch bar might be that indicated by 60 or by 91 or by 115, a system of double shank levers is employed which are of such construction that they snap into the position in which they are forced by the pressure of the respective switch bar that is pushed down. There are three of them and more would be needed if a still greater amplification and consequently more switch bars would be employed.

The first one of the double shank levers has its two shanks indicated by 130 and 131 and it is shown that they are diverging from their common pivot 132 at different angles that are so chosen that one shank as, for instance that indicated by 130 will push up its respective switch bar or simply moves up should that switch bar be pushed up already when the other shank which in this instance would be that indicated by 131 is pushed down by the switch bar 91. If then the switch bar 60 pushes down the shank 130, the shank 131 will then push up the switch bar 91. The pivot 132 is journaled in a bearing 133 that has an aperture that is downwardly elongated so that the pivot may move downward against the tension of a spring 134 that is so secured to the part forming the bearing that it bears with its two ends against both shanks in such way that only a relatively strong pressure exerted upon the shanks and the pivot will move the latter to the lower part of that bearing. Above that pivot 132 of which another one may be employed at the opposite rear side there is a little elevation or extension 135 which touches the horizontally directed upper wall of the part forming the bearing 133 which is firmly secured to the board 136. The extension 135 is then always urged by the spring 134 to snap into the corner to which it is nearest and this gives the snapping down and-up function to the buttons which is necessary for creating complete electrical connections, disconnections, respectively. The other two shanked levers 137 and 138 are of a similar construction and it deems unnecessary to describe the structure of them with the exception that the one indicated

by 137 has one shank engageable with the switch bar 91 and the other with the switch bar 115 while the double shank lever 138 having relatively longer shanks than the previously mentioned has one of its shanks arranged as to be engageable with the switch bar 60 and the other with the switch bar 115.

It will be remembered that the switch bar 40 must be in pushed down position no matter if the switch bar 60 is pushed down or not should any of the other switch bars 91 or 115 be used. This switch bar 40 is therefore operated automatically and independently from the other switch bars. The switch bar 43, however, will be pushed down by the switch bar 91. The switch bar 44 will be pushed down by the switch bar 115 and at the same time will push down the switch bar 43 by means of a bar 127, that is secured by its one end to the lowermost part of the switch bar 44 and which engages the upper side of an extension 128 that is provided for at the lower end of the switch bar 43. If the switch bar 43 is pushed down by the switch bar 91 the switch bar 44 will therefore remain in pushed up position unless it is pushed down by the switch bar 115.

For creating sufficient surface upon which the various parts such as the double shank levers, the lower switch bars and the bar 14 have to bear upon, each of the three switch bars 60, 91 and 115 has a horizontally directed extension secured to the lowermost end thereof as best seen in Figure 3 where the extension belonging to the switch bar 115 is indicated by 129. These extensions reach into the recess formed by the underside of the upper switch board 136 and the lower switch board 78.

It is apparent that any other suitable switch arrangement could substitute the switch bars. There might be used knife switches or others and in this respect the commutator scheme in connection with a dial as illustrated by the Figures 14, 15, 16, 17, 18 and 19 will suit the purpose. This scheme can be employed in connection with any radio set that has amplification in the degree as desired. It is therefore suitable for privately owned radios such as is supposed to be the one on the extreme right of Figure 4 which shows an antennae 140. By the use of the switch dial 141 the antennae can be switched out of communication with the remainder of the radio set and the latter may be switched thereby to the telephone transmitter of that set that will be described subsequently.

Referring more particularly to Figures 14, 15, 16, 17, 18 and 19, a dial 142 of the usual construction has the inscriptions "Normal voice", "Loud", "Very loud" and "Off" and these indications are so placed that each occupies one quarter of the circular space left for them. That certain space corresponds again with the positions of the contact strips 143, 144, 145 arranged on the commutator 146 in respect to a series of spring urged contacts.

In the "off" position as shown in Figure 16 the contact strip 143 which is shown in full lines in the Figures 16, 17, 18 and 19 is shown as contacting with the contacts 147 only. Since, however an electrical connection with the loud speaker 64 and the secondary coil 62 of the transformer 63 (see also Figure 5) will be established by said contact strip 143 only through the connection between the contacts 147 and 148 the commutator must be turned a quarter turn

whereby the contact strips take the position as shown in Figure 17.

If "Loud" is desired another quarter turn must be made of the commutator by means of the knob 5 150. The contact strip 144 indicated by dotted lines in Figure 18 will then come into contact with the contacts 151 and 152 which creates an electrical connection with the loud speaker 64 and with the second winding 101 of the transformer 102 (see Figure 5). The contact strip 143, however, will then be out of contact with the contact 147 whereby the connection of the secondary winding 62 with the loud-speaker 64 will be interrupted. In this position, however, 10 18 of the contact strip 144, connection of the wire 70 with the grid 76 of the vacuum tube 71 must be established (see Figure 5) and this can be done by a special contact strip also arranged on the commutator and indicated by 153 which then 20 contacts with the two spring urged contacts 154, 155.

To have the voice amplified to "Very loud" another quarter turn of the commutator will bring the contact strip 145 into contact with the 25 contacts 156, 157 as shown in Figure 19. In this instance the connection between the wire 103 of the secondary winding 101 of the transformer 102 must be established with the grid 106 of the vacuum tube 111 (see Figure 5) which will be 30 achieved by the contact strip 158 and the contact 159, 160, best seen in Figure 14.

For interrupting the circuits which in Figures 1, 2 and 3 are controlled by the switch bars 40, 43 and 44 for preventing the premature exhaustion of the batteries special contact strips and contacts are employed on the commutator 146, with insulations at the interrupting position when the commutator 146 is placed into the "off" position. The contact strips are indicated by 161, 40 162, 163 and they are discontinued at the sector that represents the "off" position. Each contact strip is contacted by two contacts 164, 165, 166, 167 and 168, 169, respectively, each pair being placed side by side but a little distanced from 45 each other. The contact 164 will then substitute the contact 81 while its next neighbor contact 165 will substitute the contact 82 of Figure 5 and the contact strip 161 will substitute the contact part 80. In a similar way will the contact strip 162 substitute the contact part 95 and the contacts 166, 167, the contacts 97 and 98, respectively, while the contact strip 163 will substitute the contact part 123 and the contacts 168, 169 will substitute the contacts 121, 122, 55 respectively.

Since it appears that sufficient interruption of the circuits is obtained therewith while the telephone amplifier is not in use no other arrangements of contacts for this purpose will be 60 necessary.

The system with the commutator switching device of Figures 14, 15, 16, 17, 18 and 19 can be employed as well in a pay station and may substitute the push buttons and switch bars together 65 with their contacts shown in Figures 1, 2 and 3. The remainder of the mechanism, however, might be retained with the exception of the rod 12 the upper part of rod 13 and the bar 14. In this instance the lever 20 while being in its lowermost 70 position has to make an electrical connection through some contacts shown by dotted lines and indicated by 170 and 171 that have to connect the wire 172 with the battery 173 (shown in Figure 5) which will make the amplifier ready for its 75 purpose. As it is desirable to have some means

for automatically turning the commutator 146 to the "off" position when the caller leaves the telephone booth there is a relatively simple mechanism employed that is illustrated schematically in Figure 20 and which consists of a flexible member 175 that is secured to some suitable part of the insulation of the commutator 146 but exactly at the opposite side of the middle of the "off" section thereof which corresponds also with the inscription "off" on the dial. At the other 10 end of that flexible member 175 is secured the weight 176 which should be just heavy enough while falling or descending to unwind the flexible member 175 and to thereby turn the commutator 146 to the position in which "off" will 15 be situated at the uppermost part of the commutator, should that commutator have been turned by hand into another position. In order to avoid the dropping of the weight 176 and the returning of the commutator to the "off" position 20 as soon as the caller removes the fingers from the knob 150 (see Figure 14) there is another flexible member 177 (see Figure 20) secured to the weight 176 and passed over two pulleys 178, 179 and by its other end it is affixed to the far-thermost point of an extension bar 180 that is 25 affixed to the lever 20. The weight of the lever 20 combined with that of the extension 180 must be in excess of that of the weight 176. It is thus evident that when the lever 20 drops together with its extention 180 the weight 176 will 30 be pulled up to its uppermost position, thus allowing the caller to turn the commutator 146 to any of the positions he desires for the amplification of the voice over the telephone without the 35 commutator being immediately returned to the "off" position. As soon, however, as the lever 20 together with its extension 180 is moved up by the bar 31 (see also Figure 2) to the horizontal position the weight 176 descends and pulls the 40 flexible member 175 thereby returning the commutator 146 to the "off" position.

An essential part of the invention is the creation of means that permit the instantaneous connection of the amplifier or any radio set with 45 the telephone. In this connection there are two types that may be employed, namely one that is permanently so installed that simply an automatic (through the introduction of a coin etc.) or manually operated switch will perform the 50 connecting with the telephone and disconnection with the antennae if it deals with a private owned radio set and the other type where the receiver of a telephone outfit is simply coupled to a transmitter of the amplifying apparatus. The last 55 mentioned type for connecting the telephone and which is also employable both in pay stations and with private owned radio sets consists of the transmitter 182 (see Figures 1, 4, 5, 6, 7, and 10) which is provided with a support 183, consisting 60 of a layer of padding material, preferably of soft rubber or sponge rubber for the purpose of preventing outside sounds from mingling with those perceived at the receiver 15 which latter is simply laid on that support made of padding 65 material whereby a spring 185 presses the receiver 15 against the portion 187 of said padding material that surrounds and partly covers also the front opening of the transmitter 182. The part of the support 183 with the padding material 70 187 against which will be laid the receiver, must have the recessed impression of at least part of the receiver that will enable the receiver to lie snugly against that padding material. There might be one or more clasps 186 employed for 75

holding the receiver firmly against the padding material so that it will even compress the latter.

For most of the pay stations it will be necessary to keep the transmitter for the amplifier as well as a special telephone receiver that is coupled thereto, out of reach of the customer in order that no damage is done to the delicate dia-

phragms thereof.

It will therefore be necessary to have a special telephone receiver arranged that is permanently coupled to the transmitter of the amplifier. Such scheme is illustrated in Figure 8 and in Figure 9 is shown the enlarged detail.

This amplifying outfit is of the pushbutton character already described in connection with Figures 1, 2 and 3, but it might just as well be of the character of the type shown with the Figures 14 to 20 inclusive and this refers also to the other couplings of the receivers with the transmitters of the amplifier shown in the drawings.

In Figure 8 there is the usual outfit of a telephone shown similar to Figure 1 with the telephone box 87 having a coin drop 17, the transmitter 208, and the receiver 15. To one of the wires 184 of the receiver 15 there is, however, another wire 188 electrically connected and to the other there is the wire 189 electrically connected and both insulated as usual with such wires and they are brought into electrical connection with a separate receiver 190. The wire 189 is directly connected to the winding 191 (see Figure 9) of the separate receiver 190, while the wire 188 is secured to the contact 192 of a switching device 35 with push button 193 that serves for temporarily interrupting the voice coming over the telephone. There is a current conducting contact part 194 normally contacting the two contacts 192 and 195 and a spring 196 is arranged for always returning the contact 194 to the position in which it contacts with the contacts 192, 195 in which position the push button 193 is pushed up. There is a wire 197 connected to the contact 195 and then connected at 199 to the winding 200 of the receiver transmitter 190 (see also Figure 9).

In Figure 1 there is also the push button 193 employed for the purpose of interrupting the voice coming over the loud speaker 64. There is, however, a little modification in the arrangement because it is to interrupt the electric connection between the wire 244 and the grid 245 (see Figure 5) and since there is only one receiver available this receiver had to be unclasped and taken from its support 183 if only the weak voice of that receiver is preferable for any reason whatsoever. The scheme in connection with the push button 193 shown in Figure 1 could, however, be employed also in connection with the amplifier of Figure 8 in which case the wire 188 would be directly connected to the winding 200.

The windings 191, 200 of Figure 9 being in the same circuit have the cores 201, 202 slightly protruding at the side where they face the dia-

phragm 203a. At their other ends they are secured to the permanent magnet 204 as usual.

The diaphragm 203 (see also Figures 12 and 13) might be of the usual construction and might be of metal but in order to avoid the so-called metallic shrillness common with the voices transmitted through the all metal dia-

phragms and for obtaining greater resonance, clarity of the words spoken and the elimination of by-sounds there is paper of the typewriting type used. That paper may have the rough texture common with such paper. Instead of

paper, however, there might be silk employed although paper is preferable. The paper or silk is then stretched on the frame 205. If it deals with paper, the sheet must be made wet with water when being mounted on the frame 205 so that it will be well stretched when it has dried. When completely dry it receives a coat of lacquer of a quality that dries hard. It might be the kind with which violins are lacquered. While the lacquer is still wet, finely divided particles of soft iron, iron files or so-called iron bronze is strewn on the lacquer especially around the sections which will face the cores 201, 202. These small iron particles become embedded in the lacquer and are held fast by the latter and since it will be these iron particles that are attracted by the electro-magnetic flux of the cores 201, 202 the iron particles being held fast by the lacquer move also the lacquered paper in the vibrations transmitted by the electro-magnetic impulse whereby the sound waves are produced by the vibration of the lacquered paper diaphragm. The cores 201, 202 should be distanced from the diaphragm 203 by about one thousandth of an inch.

This scheme is employed also with the transmitters illustrated in Figures 5, 6, 7, 10 and could be used with the transmitters of Figures 1 and 4. In Figure 11 in which a receiver is shown, the same scheme is also employed. There is an advantage over other kinds of transmitters because it can be tested upon clearness of sound and other qualities before it is assembled with the other parts of the transmitter.

These parts are dependent upon the vibrations of the diaphragm 203. It is therefore preferable to create direct contacts such as indicated by 206 which may consist of a thin piece of cork or of the light marrow of some plant. This piece is secured to the center part of the diaphragm 203 and might be secured also to the next part which is the metallic diaphragm 207. It is however, preferable to have the part 206 not secured to the diaphragm 207 but only firmly pressing thereon whereby also the paper or silk diaphragm which will have the reference numeral 203a will be completely stretched. It is to mention that whenever silk is used for the diaphragm 203a that silk must receive one or several coats of hard drying lacquer.

The diaphragm 207 might be of any suitable metal such as steel, copper, aluminum and since it is connected in an electrical circuit it should be insulated from the part 206 as well as from the diaphragm 203a. It is also to mention that the air or some gas in the space between the diaphragm 203a and the diaphragm 207 will transmit the sound vibrations of the diaphragm 203a to the diaphragm 207. For transforming the vibrations of the diaphragms 203a and 207 into electrical vibrating impulses various methods can be employed. While there is in Figures 5 and 6 a relatively large number of fine copper or silver filaments 209 secured to a copper plate 210 and which are so bent that the other ends thereof slightly touch the respective right side of the diaphragm 207 there are carbon granules employed in the scheme shown in Figure 9. In Figures 5 and 6 it is shown that to the copper plate 210 is directly connected the primary 70 winding 211 of the transformer 212. The secondary winding is indicated by 213.

The electrical circuit connections with these windings are shown in Figure 5 and will be traced later. The carbon granules 217 employed

in the scheme of Figure 9 are placed into a number of partitions or chambers 215 which each are separated from the next partition or chamber by an extension 216 of mica that is secured 5 to the copper plate 210 and which does not completely reach the diaphragm 207. The carbon granules are thereby prevented from being concentrated upon one heap because they would fall to the bottom of the large space if the extensions 216 were left away. In the scheme shown in Figure 9 they are evenly distributed over the surface of the diaphragm 207 and are not packed but each chamber 215 is provided with its certain amount of carbon granules that 10 make vibrating contacts between the diaphragm 207 and the copper plate 210.

Instead of the filaments 209 and of the carbon granules there might be a gas introduced that has electricity conducting properties as, for 20 instance mercury fumes or vapors or others known to science and should be confined in the space between the diaphragm 207 and the copper plate 210.

Referring to Figure 11 which represents a receiver that might be constructed with a regular handle or only as an ear-phone, the part that distinguishes this receiver from those up to date in use is the diaphragm 203 made of paper and provided with the lacquer coating and the iron 25 files or still smaller particles of iron in the lacquer as illustrated in Figures 12 and 13 and described already in connection with the diaphragm 203a of Figures 5, 6, 7 and 9, whereby, however, the parts are left away that belong 30 already to the transmitter such as the connection 206 and the diaphragm 207 etc. If this receiver is simply used as an ear phone it can be coupled to the transmitter of Figures 5, 6, 7, 10 by means of the clasp 220 which is constructed 40 in the fashion to snap against the hull of the receiver to press the latter sufficiently strong against the padding material 187 of the amplifier receiver. It distinguishes itself also from the clasps 186 in that no additional closing piece 45 is necessary.

The snapping-on action is obtained through the pointed or edge forming extension 221 that is in touch with a part 222 that has two sides 223, 224 converging to an edge 225 whereby a 50 relatively strong spring 226 of suitable formation presses that piece 222 against the extension 221. In the drawing of Figure 11 it is shown that the clasp 220, that is movable on the pivot 227, is pressed by the part 222 against the underside of the extension 221, thus moving and pressing the part 220 firmly against the receiver hull. If the part 220 will be lifted which requires the amount of strength that will overcome that certain part of the tension of the 60 spring 226 the side 224 of the part 222 will then press against the upper side of the extension 221 whereby the clasp arm 220 will snap into the raised or open position.

Being pushed down the part 221 snaps against 65 the underside of the extension 221 forcing the clasp arm 220 against the hull 228 of the receiver.

Referring to Figure 10 there is a structure shown with which the reaching with the finger 70 or with some tool of the easily destroyable diaphragm 203a of the amplifier transmitter, is prevented. For this purpose a relatively large space, which is the resonance-chamber 230, is created and having the wall 231 so inclined that the 75 sound coming from the diaphragm 203 or from

any other diaphragm of the receiver 15 will be reflected towards the diaphragm 203a as shown by the dotted lines 236. The wall 231 is preferably made of wood and concave in shape as shown, for obtaining an agreeable modulated 5 sound. It is shown that the aperture 235 to the resonance chamber 230 which will be open when the receiver 15 is removed and hooked up in the fashion as shown in Figure 8 the diaphragm 203a will not be reached with the fingers or with some 10 tool on account of the extension 237 reaching in a protecting way far into the resonance chamber 230.

The diaphragm 207 is best secured in the way as shown in the enlarged detail view of Figure 15 15 in which the border part of that diaphragm is grasped by a copper or brass frame 239. The wire 240 (see also Figures 5 and 6) is inserted into a hole in the frame 239 and pushed in as far as to touch the diaphragm whereby not only 20 a good contact with the frame 239 is created but also a direct contact with the diaphragm. As shown in Figure 5 the wire 240 is conducted to one side of the battery 173 and to the other side of that battery is connected the wire 242 that is 25 also connected to the contact 171 previously mentioned. The secondary winding 213 has one of its terminals connected to the wire 244 which leads to a contact 244a that contacts with the movable contact 243 and the latter with a contact 249a and the wire 249 that is connected to that contact leads to the grid 245 in the vacuum tube 61. The other terminal of the secondary winding 213 is connected by the wire 246 which leads to the contact 83. The connection with the 30 primary winding 247 of the transformer 63 is therefore interrupted through the insulation situated between the contacts 83 and 84 when the switch bar 40 is pushed up. In its pushed down position it will bring the current conducting part 40 79 into contact with the contacts 83 and 84 and the wire 248 leads to and completes the connection with the primary winding 247.

Similar arrangements are made in connection with the other units of the amplifying outfit 45 whose description of the various circuits is deemed unnecessary. This refers as well to the circuit arrangement shown in Figure 4 and it is mentioned only that A is the central or connecting station, B a pay telephone sub-station equipped 50 with a transmitter T2 and receiver R2 and with an amplifier and C is a telephone with a transmitter T3 and a receiver R3 that can be coupled to an amplifier that is convertible into a radio and supposed to be situated in a private 55 home but for convenience it is called a station. In the diagram of Figure 4 it is shown that the switch 250 has been connected to the line wire after the bulb 251 over the grounded circuit did light up upon a call from station B 60 through the connection at 53 with the contacts 54, 55 or otherwise through the hook 16. The operator in the central station did not connect the station C yet but by closing the switch 252 and pressing down the spring returned ringing 65 button 253 the buzzer 254 will be sounded in the station C through a grounded circuit that includes one of the line wires indicated by 255. By connecting the plug 256 with the line wire 257 the connection between the station B and C 70 will be established because the other line wire 258 terminating in station C is permanently connected to the line wire 259 that terminates in station B and other stations. There is also a transmitter T1 and a receiver R1 in the central 75

station A as usual. It will be noted that the talker will hear his own voice over the telephone which is of advantage because he or she can thereby find out how loud to speak or how far 5 to subdue the own voice. Means in form of the push button switch 193 described in connection with the Figure 8 enables the speaker at the telephone to cut out his own voice over the amplifier, should it prove disturbing, by simply pressing 10 with the finger on the push button 193 while at the withdrawal of the finger from the button the voice from the other connected station as well as the own voice will be heard 15 through the amplifier. If only the very low voice of the receiver 15 will be sufficient temporarily then the receiver 15 should be used and according to Figure 8 the push button 193 pressed down simultaneously. The switches 260, 261 may be 20 automatic and opened for avoiding short circuit when the bell 262 or the buzzer 254 shall be sounded.

In case that the listener at the amplifier would like to have the strength of the voice somewhat reduced, as, for instance to half the strength 25 between "Normal" and "Loud" or between "Loud" and "Very loud" there is a covering means 263 arranged as shown in Figure 1 that has to act as a damper and which may be moved to cover the whole front side of the loud speaker 30 64 or only a part of it. This covering means or damper 263 is preferably hinged to the frame of the loud speaker 64 in order that it can be moved over the front side of the latter and also moved out of that front side as shown in the 35 drawings. An inscription on the front side of that damper might be had to inform the listener of the purpose and use of the damper. That inscription might have the wording: "If voice over the amplifier is too loud use this damper and 40 move it completely or partly over the loud speaker."

On the front side panel 266 preferably behind the buttons 56, 57, 58 and 193 or on the front side panel 267 of Figure 14 directions for the 45 use of the amplifier may be had so that also people without the experience of using the amplifier may readily understand how to operate it. Beside these inscriptions the various buttons 56, 57, 58 should show the words "Normal voice", 50 "Loud", "Very loud", respectively and referring to the button 193 the inscription should read "For interrupting the voice over the loud speaker." Since the button 193 may be too small for bearing that direction a special plate 268 may 55 be provided for and placed directly behind the button 193 so that the user of the amplifier may be able to read it.

The representation in the drawings of the stepping up scheme of the voice is only illustrative and 60 there might be more electrical energy put up for obtaining the various amplifications. It must be remembered also that there are other parts that contribute to the amplification, as, for instance the receivers and transmitters of special 65 construction as set forth to which also the loud speaker 64 is to be counted and which distinguishes itself from the other receivers only through the much larger size of all its parts.

Having described my invention what is claimed 70 is:

1. In a telephone amplification system, a telephone station comprising a receiver and a transmitter, a second receiver at said station, a transmitting device permanently coupled to said second receiver, an amplifying set connected to said

transmitting device and comprising a loud speaker, and switching means incorporated in said telephone station for controlling electric circuits of said amplifying set for selectively varying the volume of sound reproduced in said second receiver and transmitted through said amplifying set. 5

2. In a telephone amplification system, a telephone station including a receiver, a transmitter, means to couple said receiver to said transmitter, 10 an amplifying device connected to said transmitter, means at said station for selectively increasing the volume of sound into said receiver and through said amplifying device, coin-controlled means for rendering effective said selective 15 means, and means also at said station for automatically interrupting the operation of said amplifying device when a person leaves said station.

3. In a telephone amplification system, a volume control apparatus consisting of a plurality 20 of electrical switches including selectively operable push buttons for actuating the same, an amplifying device including electrical circuits and vacuum tubes for the amplification of sound, said device controlled by said switches for energizing 25 the same when said switches are selectively operated, and means to automatically restore said switches and push buttons after the same have been operated.

4. In a telephone amplification system, a volume control apparatus consisting of a plurality 30 of electrical switches including selectively operable push buttons for actuating the same, an amplifying device including electrical circuits and vacuum tubes for the amplification of sound, said 35 device controlled by said switches for energizing the same when said switches are selectively operated, a depressible platform operatively connected to said switches to prepare the same for operation under the control of said push buttons, 40 and means to raise said platform to restore said switches and push buttons after the same have been operated.

5. In a telephone amplification system, a volume control apparatus, a commutator, selectively 45 operable electrical switches arranged on said commutator and including contact strips and associated pairs of contacts, an amplifying device controlled by said switches and including electrical circuits and vacuum tubes for obtaining 50 different degrees of sound amplification in accordance with the selective operation of said switches, means to operate said commutator to selectively energize said circuits to produce such modulation, and means to automatically restore 55 said commutator to a non-functioning position to interrupt said electrical circuits through said contact strips and contacts.

6. In a telephone amplification system, a volume control apparatus comprising electrical 60 switches including contacts, means to manually and selectively operate said switches, an amplifying device including electrical circuits and vacuum tubes for the amplification of sound to various degrees, said circuits being electrically connected 65 to said contacts and selectively energized by the operation of one or the other of said switches to alter said amplification through said tubes, and means to automatically restore said switches to inoperative and circuit interrupting positions. 70

7. In a telephone amplification system, an apparatus including a receiver having a vibratory member consisting of a magnetizable sheet, an electromagnet having cores disposed in proximity to said vibratory member to vibrate the same in 75

- accordance with the degree of energization of said electromagnet, a transmitter including a metallic membrane coupled to but electrically insulated from said receiver, a vibration transmitting connection between said vibratory member and said membrane, transmitting means operatively contacting said membrane for transmitting electromotive forces in harmony with the vibrations of said receiver and transmitter.
- 5 10. In a telephone amplification system, a sound volume control apparatus, comprising selectively operable electrical switches arranged for obtaining immediately one of three different stages of amplification, namely, an amplification of the sound to that of a normal voice, secondly, an amplification of said sound to that of a loud voice, and third, an amplification of said sound to that of a very loud voice, an amplifying device controlled by said switches and including electrical circuits and vacuum tubes for obtaining said three different degrees of sound amplification in accordance with the selective operation of said switches, means to operate said switches to selectively close those of said circuits to produce 15 such selected amplification, and means to automatically restore those switches to a non-functioning position that are operatively connected with those circuits and tubes that amplify said sound above the selected degree, and means for automatically nullifying any amplification over said sound volume control apparatus.
- 15 8. In a telephone amplification system, an apparatus including an electric circuit, a receiver having a vibratory member consisting of a partly metallic and partly non-metallic material, a transmitter having a metallic vibratory membrane being connected to said vibratory member and adapted to vibrate in unison with the latter and being included in said electric circuit, a metallic member spaced from said membrane, chambers formed between said membrane and metallic member, means in said chambers for transmitting to said metallic member the electromotive forces created in said circuit and accentuated by 20 said vibrations, and a transformer having primary and secondary windings, said electric circuit further including said metallic member and said primary winding for transmitting electromotive impulses to said secondary winding in conformity with said vibrations.
- 25 9. In a telephone amplification system, a transmitter having a vibratory membrane, a plate slightly spaced from said membrane, filaments secured to said plate in contact with said membrane, a transformer having primary and secondary windings, and an electric circuit including said membrane, filaments, plate and primary winding energized to transmit impulses to said secondary winding in conformity with the vibrations of said membrane.
- 30 10. In a telephone amplification system, a sound volume control apparatus, comprising selectively operable electrical switches arranged for obtaining immediately one of three different stages of amplification, namely, an amplification of the sound to that of a normal voice, secondly, an amplification of said sound to that of a loud voice, and third, an amplification of said sound to that of a very loud voice, an amplifying device controlled by said switches and including electrical circuits and vacuum tubes for obtaining said three different degrees of sound amplification in accordance with the selective operation of said switches, means to operate said switches to selectively close those of said circuits to produce 35 such selected amplification, and means to automatically restore those switches to a non-functioning position that are operatively connected with those circuits and tubes that amplify said sound above the selected degree, and means for automatically nullifying any amplification over said sound volume control apparatus.
- 35 11. In a telephone amplification system, an apparatus including a receiver having a vibratory member consisting of a fibrous sheet with iron filings embedded in it, rendering it magnetizable, an electromagnet having cores disposed in proximity to said vibratory member to vibrate the same in accordance with the degree of energization of said electromagnet, a transmitter 40 including a metallic membrane coupled to but electrically insulated from said receiver, a vibration transmitting connection between said vibratory member and said membrane, transmitting means operatively contacting said membrane for transmitting electromotive forces in harmony with the vibrations of said receiver and transmitter, a transformer having primary and secondary windings, and a circuit including said primary winding of said transformer and also said metallic membrane to transmit the electromotive impulses created by the vibrations of said membrane to the secondary winding of said transformer.

HEINRICH KARL 45
